BURNER FOR SOLID FUELS

Virginius M. Cruikshank, Shamokin, Pa.

Application September 1, 1933, Serial No. 687,734

11 Claims. (Cl. 110—36)

This invention relates to burners for coal or other similar solid fuels, in which the burner includes fuel, fire and ash supporting means over which the unignited or green fuel and fire bed is moved or impelled in a comparatively shallow layer either radially inward or radially outward from a point or points of fuel supply to a point or region where the ashes and residue are discharged, it being understood that the movement of the fuel and fire bed over the supporting means is at such a rate of speed, proportionate to the air supply or rate of combustion that the same is completely consumed by the time it reaches the region of discharge of the ashes and residue, while providing sufficient agitation of the fire bed to prevent clinker formation. The burner further includes guide means with which the fuel, fire bed and ash supporting means cooperate to effect the movement of the fuel and fire bed from the point or points of supply to the region of discharge of the ashes and residue.

The invention comprehends a guide means of the indicated character, the surface or surfaces of which are water-backed so as to prevent the fusing of ashes or cinders thereto thus avoiding collections thereon which would tend to alter their shape and interfere with the effectiveness or operativeness of the impelling means.

More particularly the invention resides in a water-backed guide means which may be fashioned as either an integral part of the fuel supply conduit or as a separate element and through which conduit the fuel is transmitted to the point or points of supply of the fuel to a grate element, the arrangement being such as to provide a barrier against the ignition of the fuel in the supply conduit by the fire on the grate element due to the continuous relative change or shifting of the portion of the grate and the fire bed with reference to the fuel supply outlet.

As a further feature, the invention aims to provide a burner in which the fuel, fire and ash supporting means are driven and rotated with reference to fixed water-backed guide means so as to cause the movement of the fuel, fire bed and ashes radially over said supporting means and in which, if desired, certain of said means are driven at relatively different rates of speed.

The invention further embodies, in a burner of the character set forth, fuel, fire bed and ash supporting means which are so constructed and arranged as to automatically effect the discharge of dirt and ashes therefrom in order to avoid

any appreciable collection on the surfaces thereof which might interfere with the proper operation of the burner.

The invention further contemplates a supporting member which is so fashioned as to provide means for causing a horizontal draft from a draft chamber to be directed away from the point or points of fuel supply and the guide means so as to drive the flame radially away from the supply, thereby further insuring against ignition of fuel in supply while aiding in the preventing of fusing of the material on the surface or surfaces of the guide means.

With particular reference to a guide means, which forms a part of an outlet conduit through which the fuel is fed onto a rotating fuel and fire bed support, the invention comprehends the provision of a fulcrumed and weighted mounting for said support to insure proper contact of the same with the combined fuel conducting and guide means, thus making for free relative movement of the parts and obviating binding.

The invention further provides ash and cinder cutting means to prevent clogging and to insure of the proper discharge of the ashes and cinders.

Other objects of the invention are to provide a more practical burner of the indicated character, which embodies comparatively few and simple parts, capable of economical production, assemblage and installation and which burner is highly efficient for the purpose intended.

With the above and other objects in view, reference is had to the following specification and accompanying drawings in which there are disclosed various forms of the invention while the claims cover modifications which properly fall within their scope.

In the drawings:

Fig. 1 is a fragmentary, vertical sectional view through a furnace equipped with a burner constructed in accordance with one form of the invention.

Fig. 2 is a horizontal, sectional view therethrough, taken approximately on a plane indicated by the line 2—2 in Fig. 1.

Fig. 3 is a sectional plan view taken on a plane indicated by the line 3—3 in Fig. 1.

Fig. 4 is a perspective view of the upper rotary clean-out plate as viewed from the underside.

Fig. 5 is a fragmentary side elevation illustrating a modified form of fuel feed and guide means.

Fig. 6 is a bottom plan view thereof.

Fig. 7 is a vertical sectional view of a further modification.

Fig. 8 is a vertical sectional view of a still further modification.

Fig. 9 is a fragmentary sectional plan view taken approximately on the line 9—9 of Fig. 8.

5 Fig. 10 is a vertical sectional view of a modified form of the fuel conduit and guide means.

Referring to the form of the invention illustrated in Figs. 1 to 4 inclusive, A designates the furnace wall and B a funnel shaped fuel feed hopper which constitutes a part of the boiler section, the same being formed to provide a water-jacket C so that the hopper is properly water-backed.

In this form of the invention, the burner includes a combined fuel, fire bed and ash supporting member, designated generally by the reference character D, and a combined fuel conduit and guide means E, the latter being shown in this instance, as an integral part of the fuel feed hopper B into which the water jacket C extends. The member E is open at its upper and lower ends and is provided with a side fuel outlet 10 which is in the nature of a notch or recess opening through the lower end of said member with the vertical side walls 11 and 12 of the fuel outlet diverging outwardly, the wall 12 being convex to serve as a guide surface. It will also be observed that the member E is provided with an extension 13 providing a sharp vertical edge which protrudes inwardly beyond the inner periphery 14, the leading surface of which extension merges into the wall 12 so as to cut the fuel column within the member E and initially urge the same outwardly through the side outlet 10 as the fuel column resting upon the fuel support is rotated therewith.

In order to promote circulation of the water in the water-jacketed or water-backed portion of the member E, a circulation pipe 15 extends downwardly within the member E and extends through and communicates with the water-jacketed or water-backed portion. A single circulating pipe 15 is employed where the member E forms an integral part of the member B but in event the member E is made as a separate section from the member B, as shown in Fig. 10 two circulating pipes 16 and 17 will be employed to obtain the proper circulation.

The fire bed supporting portion of the member D is made up of a plurality of grate plates or sections 20 having draft openings or perforations 21. These plates or sections have upwardly and outwardly flared inner edges 22 and curved rabbed under surfaces 23 at their outer edges. The fuel supporting portion of the member D includes a central portion or hub 24 having secured thereto radially projecting spider arms 25 and an outer rim 26 which support the grate plates or sections 20. The inner marginal portion of the plates between the spider arms are supported on radial lugs 27, cast or otherwise formed on the outer periphery of the central portion or hub 24. The upper portion of the hub 24 is provided with an extension 28 which is formed with an upwardly and outwardly curved and flared surface 29 slightly spaced from the inner outwardly and upwardly curved edges 22 of the plates 20 to define draft passages 30 between the lugs 27 and spider arms 25, as shown in Fig. 2, the purpose of which will be hereinafter set forth. The side margins of the plates rest upon adjacent spider arms 25 and the plates are removably secured in position by screws 31 which pass therethrough and are threadedly anchored 75 in the rim 26. The lower face of the rim 26 is

machined or faced and rests upon and is adapted for turning movement over the upper machined or faced upper edge 32 of the cup shaped body 33 which, together with the fire bed or grate and its support, defines a draft chamber 34. The body 33 has a radially outwardly projecting air intake pipe 35 which communicates therewith and extends outwardly therefrom and connects and communicates with the outlet 36 of a blower 37. The motor 38, preferably an electric motor, drives 10 the blower 37 and a shaft 39 which extends through the intake pipe 35 and into the draft chamber 34, the inner end of said shaft being journaled in a bearing 40 which is supported on a bracket arm 41 located within the draft chamber. The spider arms have secured thereto a concentric ring or annulus 42 having depressions 43 opening through the under side thereof to receive the teeth 44 of a drive pinion 45 which is secured to the shaft 39 whereby rotation is imparted to the member D, the same being turned in the direction indicated by the arrow in Fig. 2 of the drawings.

The coal or fuel feeds by gravity from the hopper member B into the combined conductor and impeller means E and obviously, the turning movement of the member D in the direction indicated by the arrow causes through the gravitational feed of the fuel against the impeller face 12, a radial outward movement of the fuel in a shallow layer, the blower functioning to supply air to the draft chamber 34 from whence the air draft emerges upwardly through the openings or perforations 21 and through the burning fuel bed. At the same time, it will be observed that the passage 30 defined between and by the surfaces 22 and 29, effects an outwardly directed horizontal draft which drives the flame radially away from the supply, thereby further insuring against ignition of the fuel at the point of supply, while aiding and preventing the fusing of material onto the guide surface or surfaces.

If desired, a pusher lug 18 may be formed on the upper surface of the hub within the member E and protruding upwardly therefrom to impart 45 rotation to the fuel within the member E so as to more positively insure the feeding and impelling of the fuel. It will also be observed that the upper surface of the portion 24 engages with and turns with reference to the lower surface of the member E thus avoiding the escape of fuel between said surface and from the member E except through the side outlet opening 10.

The upper surface of the central portion 24 is formed with a funnel shaped depression or recess 46 from which a tubular shaft 47 leads downwardly through the portion 24 and through the bottom of the body 33. The under side of the portion 24 is formed with a cylindrical depression 48 which accommodates a tubular upwardly protruding boss 49 protruding upwardly from the bottom of the draft chamber 34 and through which tubular boss the tubular shaft 47 extends. The funnel shaped depression 46 pockets the fuel and any excess water in the fuel supply will be 65 drained and conveyed away through the tubular shaft 47 which acts as a drain pipe for said excess water or moisture so that it is discharged below the fire bed and into a suitable receptacle in an ash space in the lower part of the furnace.

A clean-out means is provided for removing from the draft chamber ash dust, coal dust, or other particles which find their way into the chamber through the openings or apertures 21. As illustrated, the clean-out means consists of 75

a discharge opening 50 in the bottom wall of the draft chamber body 33 and upper and lower rotary plates 51 and 52 provided with diametrically oppositely disposed outlet openings 53 and 54. 5 The lower plate 52 is suitably keyed to the lower end of the tubular shaft 47 and is driven by and with said shaft while the upper plate is driven by means of a depending stud 55 on one of the spider arms 25 which engages with a radial arm 10 56 on the upper clean-out plate 51. The upper plate 51 is fashioned to provide an upwardly offset spiralled arm 57, the lower surface of which is slightly above the lower surface of the plate 51, which arm has its free end disposed in the direction 15 of rotation of the plate to serve as a means for gathering up and impelling inwardly the solid matter which collects in the bottom of the draft chamber 34. The lower surface of the plate 51, at the juncture of the arm 57 therewith, is extended for a distance and underlies the arm and is so fashioned as to provide a plow or shoe portion 58 having a pointed leading end facing in the direction of turning movement of the plate. The plow or shoe portion 58 functions to cleave 20 through and part the particles of matter collected on the bottom of the draft chamber so that they are either directed within the opening 53 or diverted outwardly to be subsequently engaged and directed inwardly by the arm as it moves 25 around. This construction and arrangement avoids any tendency of the particles to work under and lift the plate 51 so as to interfere with its proper operation. The upper plate 51 is formed with a central opening 59 which accommodates the upstanding tubular boss 49 which boss serves as an axle about which the plate 51 turns.

In some instances, the member D may include a separate annular section or ash ring 60 which, 40 if desired, may be driven at a relatively different rate of speed. As shown, the ash ring 60 is supported with its upper surface in a plane slightly below the plane of the upper surface of the grate plates 20 and with the inner marginal portion disposed under the concave rabbeted edges 23 of said grate plates or segments 20. A supporting annulus 61 is provided which is mounted to turn about the upper edge of the draft chamber body 33 and rests upon the upper surface of an annular bead 62 which is provided with downwardly flared apertures 63. The rim 26, in this instance, is provided with an outwardly beveled outer surface overlying the upturned flange 65 at the inner marginal edge of the annulus 61. This 45 construction serves to deflect and practically eliminate the entrance of ash dust between the confronting surfaces of the inner edge of the annulus 61 and the outer surface of the draft chamber body 33 so as to prevent such material 50 from reaching the upper bearing surface of the bead 62. However, the openings 63 will rid the upper surface of the bead 62 of any dust which reaches the same, so as to make for a smooth and unhampered turning movement of the ash 55 annulus and ash ring. The annulus 61 is provided with a series of upstanding studs 66 upon which the ash ring rests, each stud being provided with a reduced upwardly projecting end 67 which extends through a corresponding opening 68 in 60 the ash ring whereby the ash ring will be turned with the annulus. The annulus is provided in its under surface with an annular concentric series of depressions 69 to receive the teeth 70 of a pinion 71 keyed to the drive shaft 39. Obviously, the pinions 45 and 71 may be of such a

ratio as to drive the grate and ash ring at relatively different speeds.

If desired, ash cutters and impellers may be employed in connection with the ash ring and as shown, such cutters and impellers consist of 5 non-circular shanks 75, the lower ends 76 of which are received in correspondingly shaped sockets 77 in the studs 66. The upper portions of the shanks are formed with blades 78 having converging inner and outer faces 79 and 80, the blades 10 being directed inwardly at an angle to effect the cutting or breaking up of the ashes or cinders on the ash ring and the outer faces 80 functioning as impellers for pushing or camming the ashes and cinders radially outward over the outer marginal edge of the ash ring. 15

The hopper member B may be made of the closed sealed type, except for the outlet 10, and means may be provided for supplying air thereto under pressure from the blower outlet 36 such as 20 a conduit 81. This functions to circulate pure air in the hopper and also to circulate the same through the outlet 10 to insure against explosive and obnoxious gases forming in the fuel hopper and for driving the same off to be consumed in 25 the combustion chamber.

In order to provide means to further insure against clogging by cinders or clinkers and to break up and force the same downwardly between the outer edge of the ash ring and the 30 inner surface of the furnace wall A, one or more breaker shoes 82 are provided which are in the nature of angle bars attached to the inner surface of the furnace wall and inclined downwardly in the direction of turning movement of the 35 ash ring or grate.

In order to hold the upper surface of the central portion 24 of the member D in intimate contact with the lower end of the member E, the fire bed or grate element and the draft chamber, as well as the blower and motor, are preferably fulcrumed on the furnace wall A, as shown by means of trunnions 85 projecting laterally from a casting 86 on the pipe 35. The trunnions are mounted in bearings 87 provided 40 on a plate 88 which is attached to the furnace wall. The outer end of the unit is provided with a weight holder 89 upon which weights 90 are arranged to slightly overbalance the outer end of the unit so as to impinge the upper surface 45 of the hub 24 against the lower end of the member E.

In the form of the invention illustrated in Fig. 5, the member G is formed as an integral part of the member H which defines a combined part 55 of the boiler section and the fuel discharge chute. In this instance, however, the outer surface of the vertical wall 110 of the member G is helical or volute and the fuel outlet 111 is located slightly above the member G at the root of the helical or volute surface so that an underlying fuel support and grate member conveys the fuel supply around the helical or volute surface of the wall 110 from the point of supply of the fuel at the root and closer to the axis of the member G to 60 the point of said surface farthest from the axis, thus effecting a gradual radial outward movement of the fuel thereover.

In the form of the invention illustrated in Fig. 7, the stationary fuel guide member 115 is hollow 70 and disposed under the fuel outlet 116 and above the solid or central portion of the rotating fuel and fire bed supporting means 117. A conduit 118 is connected to and communicates with the interior of the member 115 and affords means for 75

circulation of water to the member to prevent fusing of ashes or cinders onto the surface thereof. This circulation may either be from the boiler section 119 or from any other suitable source 5 of supply.

In the modified form of the invention illustrated in Fig. 8 of the drawings, 120 represents the boiler section which also defines a fuel hopper 121 having a plurality of circumferentially arranged fuel outlets 122. In this instance, the fuel and fire bed support 123 underlies the boiler section and is rotated with reference thereto and the fuel outlets are disposed adjacent the outer marginal edge of the fire bed or grate element, 10 while the walls of the boiler section carry below each fuel outlet a fixed fuel guide 124 which is so constructed and arranged as to effect the radial inward movement of the fuel over the fuel and fire bed support 123. The fuel and fire 15 bed support, in this instance, has a central outlet opening 125 through which the ashes, cinders and other residue gravitate into a subterposed receptacle therefor.

What is claimed is:

25 1. In a device for burning solid fuels, a fixed fuel conduit having communication at its upper end with an overhead fuel reservoir and having an open lower end provided with a notch defining a side outlet through which the fuel is adapted to be discharged, a driven rotatable member having a central fuel supporting portion underlying the conduit, and a fire bed supporting portion surrounding said fuel supporting portion, means pivotally mounting said member 30 on a horizontal axis and means for over-balancing the member to hold the same in contact with the lower end of the conduit.

2. In a burner for solid fuels, a fixed vertically disposed tubular fuel conduit having an open 40 lower end provided with a notch defining a side outlet through which the fuel is adapted to be discharged, a driven rotatable fuel and fire bed support having a fuel supporting portion thereof located under said conduit and the fire bed supporting portion surrounding the fuel supporting portion, a wall of said outlet being spirally curved and extended inwardly to provide a guide surface against which the fuel, rotated by the fuel support, is impinged and moved radially 45 outward through the fuel outlet and over the fire bed supporting portion, said support having adjacent the juncture of the fuel and fire bed supporting portions, circumferentially arranged upwardly and outwardly directed air passages.

55 3. In a burner for solid fuels, a fixed vertically disposed tubular fuel conduit having an open lower end provided with a notch defining a side outlet through which the fuel is adapted to be discharged, a driven rotatable fuel and fire bed support having a fuel supporting portion thereof located under said conduit and the fire bed supporting portion surrounding the fuel supporting portion, a wall of said outlet being spirally curved and extended inwardly to provide a guide 60 surface against which the fuel, rotated by the fuel support, is impinged and moved radially outward through the fuel outlet and over the fire bed supporting portion, an annular ash and residue receiver and support extending around the 65 outer margin of the fire bed support and means for driving the same.

4. In a burner for solid fuels, a fixed vertically disposed tubular fuel conduit having an open lower end provided with a notch defining a side 70 outlet through which the fuel is adapted to be

discharged, a driven rotatable fuel and fire bed support having a fuel supporting portion thereof located under said conduit and the fire bed supporting portion surrounding the fuel supporting portion, a wall of said outlet being spirally curved and extended inwardly to provide a guide surface against which the fuel, rotated by the fuel support, is impinged and moved radially outward through the fuel outlet and over the fire bed supporting portion, and an annular ash and residue receiver and support extending around and disposed slightly below the outer margin of the fire bed support and a common means for driving said fuel and ash supports at 5 relatively different rates of speed. 10

5. In a burner for solid fuels, a fixed vertically disposed tubular fuel conduit having an open lower end provided with a notch defining a side outlet through which the fuel is adapted to be discharged, a driven rotatable fuel and fire bed 20 support having a fuel supporting portion thereof located under said conduit and the fire bed supporting portion surrounding the fuel supporting portion, a wall of said outlet being spirally curved and extended inwardly to provide a guide surface 25 against which the fuel, rotated by the fuel support, is impinged and moved radially outward through the fuel outlet and over the fire bed supporting portion, and an annular ash and residue receiver and support extending around and disposed slightly below the outer margin of the fire bed support, means for driving said fuel and ash supports, and means carried by said ash and residue support for cutting the ashes and residue and for impelling the same radially over the 30 outer margin thereof. 35

6. In a burner for solid fuels, a fixed vertically disposed tubular fuel conduit, having an open lower end provided with a notch defining a side outlet through which the fuel is adapted to be 40 discharged, a driven rotatable fuel and fire bed support having the fuel supporting portion thereof located under said conduit and in wiping contact therewith and the fire bed supporting portion thereof surrounding said fuel supporting portion and extending outwardly beyond the conduit, a wall of said outlet being spirally curved inwardly to provide a guide surface against which the fuel rotated by the fuel support is impinged and caused to move radially 45 outward thereover and pusher means upstanding from said support and within the conduit for imparting rotary motion to the fuel. 50

7. In a burner for solid fuels, a fixed vertically disposed tubular fuel conduit, having an open lower end provided with a notch defining a side outlet through which the fuel is adapted to be 55 discharged, a driven rotatable fuel and fire bed support having the fuel supporting portion thereof located under said conduit and in wiping contact therewith and the fire bed supporting portion thereof surrounding said fuel supporting portion and extending outwardly beyond the conduit, a wall of said outlet being spirally curved inwardly to provide a guide surface against which the fuel rotated by the fuel support is impinged and caused to move radially 60 outward thereover, said fuel and fire bed support having a funnel shaped depression in the region under said conduit and an outlet leading 65 downwardly therefrom to drain off moisture from the fuel. 70

8. In a device for burning solid fuels, a stationary upright tubular fuel conductor having an open lower end provided with a notch defin- 75

ing a side outlet through which the fuel is adapted to be discharged, a rotary fuel support underlying and closing the lower end of the conductor and extending outwardly therebeyond, and means for rotating said support, said fuel outlet having a curved guide wall towards and against which the fuel rotated by the fuel support is impinged and by which wall said fuel is directed radially outward and is caused to be moved radially over said support.

9. In a device for burning solid fuels, a stationary vertically disposed tubular fuel conduit having an open lower end provided with a notch defining a side outlet through which the fuel is adapted to be discharged, a wall of said notch being inwardly curved and extended to define a spiral fuel guide surface, a rotatable fuel and fire bed support for respectively supporting the fire bed beyond the confines of the conduit and the fuel within said conduit, means for rotating said support, and means on the fuel supporting portion thereof for imparting rotary motion to the fuel within the conduit.

10. In a device for burning solids fuels, a stationary tubular fuel conduit having an open lower end provided with a notch defining a side outlet through which the fuel is adapted to be discharged, a wall of said outlet being curved and extended inwardly beyond the inner

surface of the conduit to define a fuel guide, a rotatable fuel and fire bed support for respectively supporting the fire bed outside of the confines of the conduit and the fuel within the conduit, means for rotating said support, and 5 standing means on the fuel supporting portion for imparting rotary movement to the fuel within the conduit so as to advance the fuel towards the curved and inwardly extended wall of the fuel outlet and effect its discharge there- 10 through.

11. In a device for burning solid fuels, a driven rotatable fuel and fire bed support having a solid central fuel supporting portion and a surrounding grate portion, means for rotating said support, and a stationary fuel conduit of a diameter corresponding approximately to the diameter of the solid central portion of the support and engaged thereby, said fuel conduit having an open lower end provided with a notch defining a side 20 outlet through which the fuel is adapted to be discharged, a wall of said outlet forming a convex cam surface merging into the outer wall of the fuel conduit and towards and against which the fuel is moved by the rotation of the support 25 to cause the fuel and fire bed to be moved outwardly over the support.

VIRGINIUS M. CRUIKSHANK.
